J. GRIFFITH

BOWLING ALLEY

Filed April 23, 1923

Inventor:
James Griffith
By: Wm. B. Bell
Atty.

UNITED STATES PATENT OFFICE.

JAMES GRIFFITH, OF NEW TORONTO, ONTARIO, CANADA, ASSIGNOR TO THE BRUNSWICK-BALKE-COLLENDER COMPANY, OF WILMINGTON, DELAWARE, A CORPORATION OF DELAWARE.

BOWLING ALLEY.

Application filed April 23, 1923. Serial No. 634,104.

My invention relates to bowling alleys and has for its chief object to provide improved means for accurately centering the bowling pins in predetermined positions upon the 5 floor of the alley.

Other objects of my invention are to provide a bowling alley which has improved centering pins adapted to engage and accurately center the bowling pins in predetermined 10 positions; which has a plurality of pin spots, a plurality of improved centering pins associated with the pin spots, and means movably mounted with respect to the centering pins for bringing the centering pins into engagement with the bowling pins; and which has a plurality of centering pins and yielding means associated with each of the centering pins for disengaging the centering pins from the bowling pins.

Other objects of my invention will become apparent as the detail description progresses, reference being had to the accompanying drawing, wherein

Fig. 1 is a vertical longitudinal section 25 through a portion of a bowling alley illustrating novel features of my invention.

Fig. 2 is a bottom plan view of the mechanism shown in Fig. 1, and

Fig. 3 is an enlarged fragmentary section 30 showing in detail the construction of my improved centering pin and certain other novel features of my invention.

Similar characters of reference designate similar parts throughout the several views.

Referring to Fig. 1, the reference character 35 designates the floor of a bowling alley, having a plurality of metallic pin spots 11 secured in place by means of screws 12-12. Each of the pin spots 11 has its upper surface substantially flush with the upper surface of the floor 10, and is provided with a central tapered hole 13. It is of course understood that each of the pin spots 11 indicates the position which one of the bowling 40 pins 14 should occupy when the bowling pins are placed upon the floor 10. The holes 13 are of circular cross-section and have their axes disposed normally with respect to the upper surface of the floor 10.

As shown in Figs. 1 and 3, each of the 50 bowling pins 14 has a tapered recess 15 formed in its bottom, which is adapted to be engaged by one of a plurality of centering pins 16. Each of the centering pins 16 55 comprises a tapered shank 17, which termi-

nates at its lower end in a head 18. The tapered shank 17 of each of the centering pins 16 is loosely and slidably mounted in the tapered hole 13 of one of the pin spots 11, the shank 17 and tapered hole 13 being 60 so proportioned that when the centering pin 16 is in engagement with a bowling pin 14, as shown in Fig. 3, the shank 17 will fit snugly in the tapered hole 13 and prevent further upward movement of the centering 65 pin.

To move the centering pins 16 into engagement with the recesses 15 of the bowling pins 14, I provide a triangle 20 disposed beneath the floor 10 of the bowling alley and 70 slidably mounted in a plurality of straps 21 rigidly secured to the floor 10 by screws 22. The heads 18 of the centering pins 16 rest upon the upper surface of the triangle 20, and it is apparent that if the triangle 20 is 75 forced upwardly, the several centering pins 16 will be moved into the positions wherein they engage the bowling pins 14, as illustrated in Fig. 3.

The means for displacing the triangle 20 80 to obtain operative engagement between the centering pins and the bowling pins 14 comprises a lever 34, pivotally secured with respect to the floor by means of a pin 35, the forward end of the lever 34 being pivotally 85 secured to the triangle 20 through the medium of a pin 36. A treadle 37 is provided at the other end of the lever 34, and by stepping upon this treadle the operator may cause the desired displacement of the triangle 20.

I have shown and described means for raising the centering pins 16 into positions wherein they operatively engage the bowling pins 14, but neither the particular means 95 employed nor the details thereof are a part of this invention, as any suitable means may be employed for actuating the centering pins 16.

I have provided each of the centering pins 16 with a helical compression spring 38 loosely wound around the tapered shank 17 of the centering pin and adapted to rest upon the upper surface of the head 18 of the centering pin. Each of the helical compression springs 38 is so proportioned that when its associated centering pin is in the position shown in Fig. 3, the spring will be compressed and will prevent the centering pin from freezing in either the tapered hole 13 of 105 110

the pin spot 11 or the tapered recess 15 of the bowling pin 14. Unless the centering pin 16 is actually wedged in the tapered hole 13 or the tapered recess 15, the weight of the head

18 of the centering pin is sufficient to keep the centering pin in engagement with the upper surface of the triangle 20 at all times.

In the operation of the device the operator steps upon the treadle 37 causing the centering pins 16 to be raised to positions wherein the tapered shanks 17 fit snugly in the tapered holes 13, as illustrated in Fig. 3. The bowling pins 14 are then placed upon the pin spots 11, the recesses 15 registering with the centering pins 16. As the tapered shanks 17 of the centering pins 16 are designed to fit snugly within the tapered recess 15, when the centering pins are in their uppermost positions, as determined by the tapered holes 13 in the pin spots 11, the bowling pins 14 will be accurately centered upon the pin spots 11. Releasing the treadle 37 will permit the triangle 20 to return to its lowermost position with respect to the floor 10, and the weight of the several centering pins 16 will cause them to follow the triangle 20 and to rest upon its upper surface when it has reached its lowermost position. If the centering pins 16 tend to become lodged or wedged in the recesses 15 or the holes 13, the compression springs 38 will disengage the centering pins from the bowling pins or from the pin spots. Similarly, if the triangle 20 becomes caught in its uppermost position, the springs 38 will act thereon to cause it to return to its lowermost position.

It is readily understood that damaged centering pins may be replaced with new centering pins by removing the screws 12 securing the pin spots 11 to the floor 10, the centering pins and pin spots being self-

aligning, thus obviating the necessity of arranging the new centering pins with respect to the other centering pins or with the triangle 20.

I am aware that changes in the form, construction and arrangement of parts may be made without departing from the spirit and without sacrificing the advantages of the invention and I reserve the right to make all such changes as fairly fall within the scope of the following claims.

I claim:

1. The combination of a bowling alley bed having a plurality of openings therein, a frame beneath the bed, a plurality of pins arranged in said openings and having weighted heads resting freely upon the frame, and means for moving the frame to thrust the pins upward in the openings.

2. The combination of a bowling alley bed having a plurality of openings therein, a frame beneath the bed, a plurality of pins arranged in said openings and having weighted heads resting freely upon the frame, means for moving the frame to thrust the pins upward in the openings, and springs on the pins resting upon the heads and adapted to be compressed when the pins are moved upward to assist in retracting the pins.

3. The combination of a bowling alley bed, a plurality of pin spots seated in the bed and having pin openings therein, a frame beneath the bed, a plurality of pins arranged in said openings and having weighted heads resting freely upon the frame, means for moving the frame to thrust the pins upward in the openings, and springs on the pins and adapted to be compressed between the pin spots and the heads to assist in retracting the pins.

JAMES GRIFFITH.
